UNITED STATES PATENT OFFICE.

HEINRICH BAUMEISTER, OF PANKOW, GERMANY, ASSIGNOR TO GENERAL ELECTRIC COMPANY, A CORPORATION OF NEW YORK.

MULTISTAGE SUCTION FAN FOR VACUUM CLEANERS AND THE LIKE.

Application filed May 18, 1923. Serial No. 639,765.

To all whom it may concern:

Be it known that I, HEINRICH BAUMEISTER, a citizen of the German Realm, residing at Pankow, Germany, have invented 5 certain new and useful Improvements in Multistage Suction Fans for Vacuum Cleaners and the like, of which the following is a specification.

The present invention relates to suction 10 fans such as are used in connection with vacuum cleaners and the like and has for its object to provide an improved structure and arrangement wherein with a single vane wheel or impeller I am enabled to provide a 15 multistage suction-producing fan of this type.

For a consideration of what I believe to be novel and my invention, attention is directed to the following specification and the 20 claims appended thereto.

In the drawing, Fig. 1 is a vertical, sectional view of a suction cleaner equipped with a suction fan or suction-producing mechanism embodying my invention: Fig. 25 2 is a sectional view through the suction-producing device: Fig. 3 is a transverse, sectional view, and Fig. 4 is a diagrammatic, perspective view illustrating the path of the air as it flows through the multi-stage 30 fan.

Referring to the drawing, the vane wheel *a* provided with a vane *b* rotates between two stationary drums *c* and *d*. The vane wheel *a* with the vane *b* thereon forms a 35 suction fan and it is shown as being connected to the shaft of an electric motor *v* by which it is driven. The inner drum *c* is divided by the partition *e* into two chambers *f* and *g*. The two drums *c* and *d* are 40 attached directly to a wall *w* of the casing of the suction cleaner. The chamber *f* is the admission chamber to the fan and communicates through an opening *h* in the wall *w* with the region from which the air is to be 45 drawn. In the present instance, this is the chamber 5 located beneath the filter plate *x* of the vacuum cleaner. The drum *c* is provided with a recess *i* through which the air which has been drawn up can pass into the 50 vane wheel. Air is discharged from the vane wheel through a recess *k* in the outer drum into the hollow space *l* which is formed by a cylinder or casing wall *m* and is bounded by the partition walls *n*, *n'*. From this 55 space the air passes through an opening *o*

in the wall *w* into a passage *p* which is formed by a sheet metal cap *q* and opens through an opening *r* into the chamber *g* in the inner drum. From here the air passes through the opening *s* for the second time into the vane wheel and is discharged therefrom through the opening *s'* into an outer chamber *t* whence it escapes through a discharge opening *u* into the open air. By this arrangement it will be seen that the air is acted upon twice by the impeller thereby obtaining the effect of a multi-stage apparatus. By this means I am enabled with a single impeller to obtain a much greater suction than has heretofore been possible and at the same time utilize a lower speed for the revolving fan. In vacuum cleaners having only a single stage fan the speed of the motor must be relatively high in order to produce sufficient suction for efficient cleaning and this is objectionable on account of the difficulties in manufacturing and keeping in operative condition a high speed apparatus. By my invention I am enabled to obtain equally 70 good results with a much lower speed motor.

It will be noted that the piece of sheet metal *q* which divides the passage *p* is located inside the vacuum cleaner casing so that it does not take up any outside space. 85 It may with advantage also serve as a support for the filter *x*.

In the present invention I have shown a two-stage arrangement, that is, one in which the air is acted upon by the impeller twice 90 in passing from the inlet opening to the discharge opening. I may, however, in a similar manner provide more than two stages if found desirable.

In Fig. 1, 6 and 7 indicate the handles of 95 the vacuum cleaner, 8 the suction nozzle and 9 the casing which is divided by the filter member *x*. In operation, the suction nozzle is moved over the surface to be cleaned in the usual manner, the dust-laden air being 100 drawn through the nozzle into the cleaner casing. Here the air passes through the filter *x* which may be formed of cloth or other suitable material while the particles of dust are caught by the filter and retained 105 in the casing.

It will be understood, of course, that the particular type of cleaner with which my invention is shown is illustrated only by way of example and that the invention may be 110

embodied in connection with any suitable type of vacuum cleaner. It will also be understood that such a mechanism embodying my invention may be used in connection with 5 any apparatus or for any purposes to which it may be found applicable.

In accordance with the provisions of the patent statutes, I have described the principle of operation of my invention, together 10 with the apparatus which I now consider to represent the best embodiment thereof, but I desire to have it understood that the apparatus shown is only illustrative and that the invention may be carried out by other 15 means.

What I claim as new and desire to secure by Letters Patent of the United States, is:—

1. In an apparatus of the character described, the combination of a casing having 20 an inlet opening and an outlet opening, an impeller in the casing, a wall which surrounds the impeller in spaced relation to the casing, said wall having openings which communicate with the periphery of the impeller at spaced points, partition means between said wall and casing providing a discharge chamber for each wall opening, means providing a plurality of inlet chambers for said impeller, and walls which define 25 a passage connecting one of said outlet chambers to one of the inlet chambers.

2. In an apparatus of the character described, the combination of a casing having an inlet opening and a discharge opening, 30 walls forming a pair of spaced drums in the casing, a suction fan having vanes which

revolve between said drums, and partition walls and passages in said drums for directing the medium being pumped to and from said vanes a plurality of times in flowing 40 from the inlet opening to the discharge opening of the casing.

3. In combination, two concentric walls with partitions between them to form a plurality of chambers one of which is a discharge chamber, an inner, annular wall divided into a plurality of chambers one of which is an admission chamber, and an impeller having vanes which revolve between said inner wall and the outer walls, said 50 walls having passages for directing medium being pumped from the admission chamber a plurality of times through the impeller to the outlet chamber.

4. In an apparatus of the character described, an impeller wheel having vanes thereon, an inner annular wall having partition means therein to form a plurality of chambers which communicate with the admission sides of the vanes at different points, 55 an outer annular wall in spaced relation to the casing, partition means between said last named wall and the casing which forms therewith a plurality of chambers which communicate with the discharge sides of the vanes at different points, and a wall which forms a passage connecting an inlet chamber to an outlet chamber.

In witness whereof, I have hereunto set my hand this 28th day of April, 1923.

HEINRICH BAUMEISTER.
